UNITED STATES PATENT OFFICE.

CHARLES A. LITTLEFIELD, OF LOWELL, MASSACHUSETTS, ASSIGNOR TO THE DRAPER COMPANY, OF PORTLAND, MAINE, AND HOPEDALE, MASSACHUSETTS.

WARP STOP-MOTION FOR LOOMS.

SPECIFICATION forming part of Letters Patent No. 643,299, dated February 13, 1900.

Application filed November 3, 1899. Serial No. 735,655. (No model.)

To all whom it may concern:

Be it known that I, CHARLES A. LITTLEFIELD, of Lowell, county of Middlesex and State of Massachusetts, have invented an Improvement in Warp Stop-Motions for Looms, of which the following description, in connection with the accompanying drawings, is a specification, like letters on the drawings representing like parts.

10 This invention has for its object the production of novel stop-motion mechanism adapted particularly for use in looms, although not restricted thereto.

In carrying out my invention I employ a series of movable detectors which are normally maintained inoperative by intact warps, the detectors engaging the warps in a peculiar and novel manner. Leasing members are provided which divide the warps into groups 20 which form the planes of the shed, and between the said members the warps of the two groups cross each other, and in accordance with my invention each detector engages two crossed warps at their crossing, being held 25 inoperative thereby. Should either warp of the pair fail, the detector controlled thereby will move into operative position and similar stopping means will be actuated by or through such abnormal positioning.

30 I have herein illustrated one embodiment of my invention as applied to a loom as the most general application thereof, but my invention is not restricted to such use or application.

35 Figure 1 is a sectional view of a loom, taken from front to rear, with one embodiment of my invention applied thereto. Fig. 2 is a partial sectional view thereof on the line xx , Fig. 1, looking toward the left, the leasing 40 members and warps being omitted; and Fig. 3 is an enlarged perspective detail showing clearly the manner in which a detector engages the pair of crossed warps.

The loom-frame A, breast-beam A^{40} , the lay A^3 , and the lay-swords, one of which, as A^4 , is herein shown, the shipper S, and the loom-harness H may be of any usual or well-known construction.

45 As shown in the drawings herein, a knock-off lever a is pivoted to the loom-frame to

throw the shipper S out of its usual holding-notch when the loom is to be stopped, said knock-off lever being pivotally connected at a' with a knock-off rod a^2 , mounted to slide in suitable bearings a^3 on the loom side, the 55 rear end of the rod being offset, as at a^4 .

I have herein shown a bunter b as movable with the lay and for convenience pivotally connected at b^x with one of the lay-swords, the normal reciprocation of the bunter being 60 out of range of the bent end a^4 of the knock-off rod. The bunter is herein shown as sustained and guided in its movements by a support, shown as a flat bar or plate c , set upright and with its lower edge toothed; as at c' , (see 65 Fig. 2,) and attached at its ends to arms c^2 , fulcrumed at c^x on the loom side, a stop c^3 under the inner end of one or both of the arms limiting the downward movement of the support c , so that normally the latter will 70 be in the position shown in Figs. 1 and 2 and held stationary, the bunter sliding back and forth thereover as the lay reciprocates. A feeler f , shown as a flat plate, preferably notched or toothed, as at its upper edge, as at 75 f' , Fig. 2, is attached to rocker-arms f^2 , fulcrumed at f^x on the outer ends of the rocking supports or arms c^2 . A link f^4 , pivotally connected with one of the feeler-arms at its upper end, is loosely connected at its lower 80 end with a lifter-arm f^5 , fulcrumed at f^6 on a bracket secured to the loom-frame, said lifter-arm being provided, preferably, with a roller f^7 to travel on a cam C, mounted on a shaft C^x of the loom, which may be the usual 85 cam-shaft, the double-throw cam C operating to lift the feeler twice for every revolution of the shaft C^x , so that the upper edge thereof will approach very closely the bar c , and when the apparatus is running properly this vibrat- 90 ing movement of the feeler continues.

The leasing devices herein shown are the usual lease-rods L L', the warps being divided thereby into groups, the warps in one group, as w , Fig. 3, crossing the warps w' of the 95 other group at the point w^x between the lease-rods in usual manner.

A series of detectors d are herein shown as pivotally mounted on a transverse shaft or rod d^x , extended across the loom, the lower 100

ends of the detectors being bent or offset at d' toward the path of the feeler, but normally maintained out of engagement with the latter. The upper end of each detector is extended 5 between the leasing members to engage a pair of crossed threads at the crossing w^x thereof, as shown most clearly in Fig. 3, it being shown therein that the detector crosses either warp at the side opposite to which said warp engages 10 the other one of the pair. Manifestly the detectors will be maintained in the position shown and inoperative so long as the crossed warps of each bar remain intact, but should either warp fail then the detector will 15 be free to slide along the other warp toward the back of the loom, the portion of each detector above its fulcrum being the heavier, such movement of the detector into operative position interposing its finger between the 20 feeler and bunter-support c . After such interposition the feeler will at its next upward stroke engage the finger and press it against the toothed edge of the support c , so that at that time the feeler and the support will rock 25 in unison on the fulcrum c^x to thereby raise the bunter b , so that at the next forward movement of the lay the bunter will engage the bent end a^4 of the knock-off rod and move the latter in the direction of the arrow 10, Fig. 1, 30 to release the shipper, and thereby stop the loom. Under normal conditions the feeler is vibrated about the fulcrum f^3 and relatively to the bunter-support c , but the interposition of the detector-finger d' will cause both the support 35 and feeler to move in unison on the fulcrum c^x .

The shipper and the usual belt-shifting mechanism, not herein shown, together with the knock-off devices and the bunter, constitute 40 stopping means normally inoperative and actuated by or through the abnormal positioning of a detector due to failure of one or both of its controlling-warps.

The notching or serrating of the opposed 45 jaws c' and f' of the support and feeler, respectively, is to prevent twisting of the finger portion of the detector when interposed therebetween.

My invention is not restricted to the precise 50 construction or arrangement of parts as herein shown, as the same may be variously modified, but so far as I am aware it is broadly new in warp-stop-motion mechanism to maintain detectors in inoperative position by engagement with two crossed warps, the crossing 55 being formed by some form of leasing device.

Having described my invention, what I claim, and desire to secure by Letters Patent, 60 is—

1. In warp-stop-motion mechanism, leasing members, a series of detectors maintained inoperative by engagement with pairs of warps at their crossing-point between the leasing members, said detectors resting against the threads at the crossings thereof, and stopping means operated by or through abnormal po-

sitioning of a detector due to failure of one or both of its controlling-warps.

2. In warp-stop-motion mechanism, leasing 70 members, a series of angularly-movable detectors maintained inoperative by engagement with pairs of warps at their crossing between the leasing members, a fixed pivotal support for the detectors and stopping means, 75 operated by or through abnormal positioning of a detector due to failure of one of its controlling-warps.

3. In warp-stop-motion mechanism, leasing 80 members, a series of angularly-movable detectors having each an offset lower end and maintained inoperative by engagement with pairs of warps at their crossing between the leasing members, a normally-moving, coöperating feeler, and stopping means actuated by 85 or through engagement of the feeler and the offset end of an abnormally-positioned detector due to failure of one of its controlling-warps.

4. In warp-stop-motion mechanism, parallel 90 and separated leasing members to divide the warps into groups, a series of movable detectors each adapted to engage a warp in each group at the crossing-point of such warps between the leasing members and be maintained 95 inoperative, and stopping means, actuated by or through a detector operatively positioned by failure of one of its controlling-warps.

5. In warp-stop-motion mechanism, a series 100 of detectors maintained inoperative by intact warps, each detector having an offset finger, a two-part feeler comprising a pivotally-mounted member and a member normally movable relatively thereto, and stopping means, including a bunter controlled by the 105 pivoted member of the feeler, movement of a detector into operative position interposing its finger between the members of the feeler, to effect their simultaneous movement, to thereby move the bunter into operative position.

6. In warp-stop-motion mechanism, a series 110 of detectors maintained inoperative by intact warps, each detector having an offset finger, a coöperating vibrating member, stopping 115 means including a bunter, and a pivoted support therefor, to which the vibrating member is fulcrumed, movement of a detector into operative position interposing its finger between the support and vibrating member, whereby 120 movement of the latter operatively positions the bunter.

7. In warp-stop-motion mechanism leasing 125 members to divide the warps into groups, a series of detectors pivotally mounted below the warps and upturned to respectively engage and rest against a warp in each group at their crossing between the leasing members, a fixed fulcrum for said detectors, a vibrating feeler, and stopping means actuated 130 by or through engagement of the feeler with the lower end of a detector operatively positioned by failure of one of its controlling-warps.

8. In a loom, the lay, a bunter pivotally connected therewith, stopping means for the loom, including a link normally out of range of the bunter, a movable support for the bunter, a series of detectors maintained inoperative by intact warps, each detector having an offset finger, and a vibrating feeler, movement of a detector into operative position interposing its finger between the feeler and bunter-support, to thereby effect movement of the bunter-support to operatively position the bunter.

9. In a loom, the lay, a normally-inoperative bunter pivotally connected therewith, stopping means, actuated by the bunter, a

rocking support for the bunter, a stop to limit movement of the support in one direction, a series of detectors maintained inoperative by intact warps, and a coöperating feeler fulcrumed on the bunter-support, movement of 20 a detector into operative position effecting movement of the bunter-support by the feeler, to operatively position the bunter.

In testimony whereof I have signed my name to this specification in the presence of 25 two subscribing witnesses.

CHARLES A. LITTLEFIELD.
